UNITED STATES PATENT OFFICE

2.455.750

SCRAP SEPARATOR FOR MATERIALS CONVEYER

Edward A. Freed, Moline, Ill.

Application April 3, 1944, Serial No. 529,247

7 Claims. (Cl. 198—64)

1

The present invention relates generally to materials conveyors and more particularly to that class of conveyors which comprises a tubular conduit, within which is disposed a propelling device, such as an auger, for conveying stoker coal, grain, or other fluent solids. The principal object of my invention relates to the provision of a separator for removing from the fluent solids any large infrangible objects which would be likely to damage the conveyor, such as, for example, mine spikes, rocks, etc.

This invention is advantageously applied to a stoker in a coal burning furnace, for it is well known to those skilled in the art that pieces of scrap metal frequently find their way into the hopper and become wedged or jammed between the conveyor auger and the entrance to the conveyor tube. Heretofore, it has been customary to provide shearable coupling pins between the auger and its driving motor, but although a shear pin may prevent severe damage to the apparatus, it does not avoid an interruption in the operation of the stoker and requires the removal of the obstruction before operation can be resumed. A further object of my invention, therefore, relates to the provision of a separator which removes the obstructing object from the conveyor before it has become jammed, and deposits the object safely in a receptacle, which can be cleaned out at any convenient time.

In the accomplishment of these objects I have recognized that an obstructing object is a hazard to the operation of the conveyor as long as it remains in a position above the conveyor auger, but the hazard is removed by transferring the object from above the auger to below the latter, since the specific gravity of the piece of scrap iron is greater than that of the coal and insures that the piece will not again rise into engagement between the auger vane and the tube.

Another object of the present invention, therefore, relates to providing for means responsive to movement of the auger for positively urging the object from a position above the conveyor to a position beneath the latter. A related object of my invention relates to the provision of a receptacle into which the objects are delivered for retaining them until an opportunity is found for removing them at a time when the stoker is not in use.

Still another object of the invention relates to the provision of means for quickly and easily withdrawing the accumulation of scrap iron and other deleterious matter.

These and other objects and advantages of

2

my invention will become apparent to those skilled in the art after a consideration of the following description, in which reference is had to the drawings appended hereto, in which

5 Figure 1 is a top plan view of a fuel conveyor between a hopper and a furnace retort, the hopper and retort being partially broken away; Figure 2 is an elevational view taken in section along a line 2—2 in Figure 1;

10. Figure 3 is an elevational view of one edge of the separating device, as indicated by a line 3—3 in Figure 2; and

Figure 4 is an elevational view of the other end of the separator, as indicated by a line 4-4 in Figure 2.

Referring now to the drawings, the fuel hopper 5 comprises side walls 6 and end walls 7, and a bottom including a conveyor trough 8 having a pair of upwardly diverging side plates 9 for directing the granulated fuel, such as stoker coal, into the trough 8. The furnace retort is indicated by reference numeral 10 and is not shown in detail since any conventional retort or other appropriate fuel burning device can be employed.

25 The fuel is delivered to the retort 10 through a cylindrical tube or conduit 11, which is connected with the conveyor trough 8 through a separator indicated generally by reference numeral 15, adapted to separate from the flow of coal to the retort 10 any scrap metal or other objects which might damage the fuel conveying apparatus.

The separator 15 comprises a hollow body or housing 16 connected serially between the hopper 5 and the retort tube 11. The housing 16 is provided with flanges 17, 18 at its inlet and outlet ends, respectively, which are rigidly bolted to registering flanges 19, 20 on the hopper 5 and tube 11, respectively. Preferably, the housing 16 is formed in a single casting, and is provided with a cylindrical passage 21 extending longitudinally through the housing in axial alignment with the hopper trough 8 and the retort tube 11.

45 An auger or screw conveyor 25 extends coaxially through the trough 8, passage 21 and tube 11 into the retort 10 and comprises a shaft 26 and a continuous helical vane 27 which fits closely but rotatably within the trough, passage, and tube. The outer end of the shaft 26 extends outwardly of the hopper 5 and is rotatably driven in the direction indicated by arrows in Figures 2 and 4 by an electric motor (not shown) or other suitable mechanism.

55 The housing 16 is provided with a chamber 30 alongside the passage 21 extending above and

below the latter and defined by a side wall 31 spaced laterally from the passage, a bottom 32, a top wall 33, an inner end wall 34 inclined laterally toward the passage 21 at the outlet end of the housing and a curved central wall 35 over the passage 21, extending vertically downwardly from the top wall 33 and terminating at its intersection with the passage 21 along a helical edge 36. The passage 21 communicates with the chamber 30 by means of a large opening 10 extending from end to end of the passage, and defined by the helical edge 36 along the top of the opening and a straight lower edge 37 extending axially along the bottom of the passage. The helical edge starts at the entrance end of the passage 21 on the side of the passage opposite the chamber 3 and curves upwardly over the auger 25 and down the side of the latter adjacent the chamber 30, terminating near the outlet end of the housing near the bottom of the passage. Thus, the helical curve of the edge 36 winds in the opposite direction to the helical vane 27 and has a pitch much greater than that of the vane.

Hence, it will be evident that the upper portion of the chamber 30 extends over the auger 25 at the entrance end of the housing, forming an enlarged or flared entrance 38, which registers with an upwardly enlarged exit opening 39 in the hopper wall 6 above the trough 8, through which the granulated stoker fuel is free to flow.

The housing is also provided with a recess or channel 40 extending under the passage 21 from one end to the other of the housing, which registers with a clean-out passage 41 in the hopper under the trough 8. The flange 20 on the retort tube 11 is extended down to cover the inner end of the channel 40.

With the hopper 5 filled with stoker coal, the auger 25 is rotated to propel the fluent fuel from the trough 8 through the passage 21 and tube 11 into the retort 10. The fuel overflows through the large opening between the helical edge 36 and the lower edge 37 into the recess 40, filling the chamber 30 up to the top wall 33, but after these spaces within the housing are filled, the coal remains stationary except that between the convolutions of the vane 27.

In the event that a piece of scrap iron or other extraneous object finds its way into the hopper and is carried into the housing 16 by the auger 25, there is no damage resulting from the object being caught between the auger vane 27 and the top of the housing, which sometimes occurs in the conventional conveyor where the end of the retort tube 11 is connected directly to the hopper. Because of the flared entrance 38 above the auger there is ample room for the usual piece of scrap, illustrated by a spike 43, to pass into the housing over the auger.

Since the specific gravity of the metal spike 43 is greater than that of the fluent coal, the spike will readily sink to the bottom of the channel 40 or chamber 32 whenever the spike slides off the auger. However, when the spike tends to ride along on top of the auger, it becomes engaged between the auger vane and the helical upper edge 36 of the opening, but in view of the large pitch of the helical edge it cannot become jammed between the latter and the auger vane but is propelled longitudinally by the camming action of the vane cooperating with the edge 36, and since the spike follows the helical edge around the auger, it is evident that the spike will be transferred from a position above the auger

to the side or bottom of the auger until it drops away from the latter and sinks into the bottom of the channel 40. The channel or chamber serves as a receptacle to retain the spike and other foreign objects without any danger of their interfering with the operation of the conveyor. As the spike sinks into the recess, it may be engaged by the bottom of the vane, which merely pushes it along the channel, tending to lay it longitudinally therein.

Of course, any foreign objects that are carried along the bottom of the trough in the hopper do not become a menace to proper operation of the conveyor, for they merely slide over the lower edge 37 into the recess.

Thus, it will be appreciated that since there are no edges around the passage 21 lying in radial planes, there is no possibility of the spikes and other foreign objects becoming jammed and therefore there is no necessity for shear pins, slip clutches or other safety devices between the auger shaft 26 and its driving motor.

Furthermore, inasmuch as there is ample room in the bottom of the chamber 25 to retain an appreciable quantity of extraneous objects, it is seldom necessary to take the time to clean out the recess during the heating season, for the recess can be cleaned out in the spring when the apparatus is shut down.

It is to be understood that while I have disclosed a preferred embodiment of my invention, I do not intend to limit my invention to these particular details shown and described. Furthermore, my invention is not limited to stoker conveyors for it is also advantageously applied to other types of conveyors, such as, for example, conveyors for grain or for other fluent solids.

What I desire to protect by Letters Patent is set forth in the claims which follow.

I claim:

1. In a materials conveyor, a housing having a generally cylindrical passage therein, an auger rotatably disposed in said passage and provided with a continuous helical vane fitting closely within the latter for moving material from said housing into said passage and longitudinally therethrough, a portion of the top and one side of said passage being open within said housing and having a generally helical edge defining the opening curving over said passage and down said one side, said edge and said vane being cooperable to force infrangible objects caught therebetween to the bottom of said passage, said housing having a recess beneath said auger for collecting said objects.

2. For use with a hopper for fluent solids, a materials conveyor comprising a housing having a flared entrance adapted to communicate with said hopper and a cylindrical passage, an auger extending through said entrance from said hopper

and through said passage and having a continuous helical vane fitting closely within the latter for moving the fluent solids from said hopper into and through said passage, a portion of said passage having an opening communicating with the interior of said housing, said opening being defined by a continuous helical edge curving over the top of said auger in a direction counter to that of said auger vane, said edge extending down said one side of said auger and terminating near the bottom of the latter, said vane being cooperable with said edge to urge by a camming action, infrangible objects caught therebetween to the bottom of said passage, the bottom of said passage being recessed to collect said objects.

3. For use with a conveyor of the type comprising

ing a cylindrical conduit and an auger rotatably disposed therein, apparatus for separating infrangible objects from the material to be conveyed, comprising a separator housing adapted to be connected in serial relation with the conveyor tube and serving as an entrance for the latter, said housing having a tubular passage therein adapted to register with said conduit to receive said auger, means associated with said housing adjacent to and cooperable with said auger for forcing to the bottom of said passage objects that are too large to readily pass therethrough, said housing including a channel in the bottom of said passage for receiving said objects.

4. Apparatus for handling fluent solids and the like, comprising a casing having a conveyor trough therein having a tubular passage in alignment with said trough, conveying means movable in said trough and passage for propelling said solids therethrough, a guide shield over said trough adjacent the entrance to said passage having an oblique guide edge extending over said trough and downward along one side thereof adjacent to and cooperable with said conveying means to cam infrangible objects from above said conveying means to the bottom of said trough, there being a recess below said trough serving as a receptacle for said objects to prevent damage to said conveying means.

5. Apparatus for handling fluent solids and the like, comprising a casing having a conveyor trough therein and a tubular passage in alignment with said trough, conveying means movable in said trough and passage for propelling said solids therethrough, a guide shield over said trough adjacent the entrance to said passage having a helical guide edge extending from one side of said trough over the latter and downwardly over the other side of the trough, terminating near the bottom thereof adjacent to and cooperable with said conveying means to cam infrangible objects to the bottom of said trough, there being a channel in said casing recessed in the bottom of said trough and extending axially beneath said conveyor to serve as a receptacle for said infrangible objects to separate them from the fluent solids conveyed by said conveying means.

6. In a materials conveyor, a housing having a generally cylindrical passage therein, an auger rotatably disposed in said passage and provided with a continuous helical vane for moving material from said housing into said passage and longitudinally therethrough, a portion of the top and one side of said passage being open within said housing and having a generally helical edge defining the opening curving over said passage and down said one side, said edge and said vane being cooperable to force infrangible objects caught therebetween to the bottom of said passage, the lower edge of said opening extending axially along the bottom of said passage, there being an open space in said housing alongside of and beneath said passage to form a receptacle for said objects.

7. For use with a hopper for fluent solids, a materials conveyor comprising a housing having a flared entrance adapted to communicate with said hopper and a cylindrical passage, an auger extending through said entrance from said hopper and through said passage and having a continuous helical vane for moving the fluent solids from said hopper into and through said passage, a portion of said passage having an opening communicating with the interior of said housing, said opening being defined by a continuous helical upper edge curving over the top of said auger, said upper edge extending down said one side of said auger, and a lower edge extending axially along the bottom of said passage, said housing having side and bottom walls spaced laterally and downwardly from said upper and lower edges of said opening, respectively, to provide a receptacle for said infrangible objects.
